Primary Examiner — Alison M Ofstun(57) **CLAIM**

The ornamental design for a facial cleaning brush, as shown and described.

DESCRIPTION

FIG. 1 is a front elevational view of a facial cleaning brush showing my new design;

FIG. 2 is rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof; and,

FIG. 9 is a front and top perspective view thereof.

In the drawings, the broken lines illustrate portions of the article which form no part of the claimed design.
